UNITED STATES PATENT OFFICE.

MORITZ L. MUELLER, OF SEATTLE, WASHINGTON, ASSIGNOR TO NORTHWEST BLOWER KILN COMPANY, OF SEATTLE, WASHINGTON, A CORPORATION OF WASHINGTON.

METHOD OF AND APPARATUS FOR KILN-DRYING LUMBER.

Application filed April 21, 1923. Serial No. 633,688.

To all whom it may concern:

Be it known that I, MORITZ L. MUELLER, a citizen of the United States of America, and resident of the city of Seattle, in the 5 county of King and State of Washington, have invented certain new and useful Improvements in Methods of and Apparatus for Kiln-Drying Lumber, of which the following is a specification.

10 My invention relates to kilns for drying lumber, and particularly to a kiln which is designed to dry lumber while piled on edge.

The object of my invention is to provide a method and means for drying lumber in 15 this way, which will in some respects be simpler and which also will be more effective than the previous methods and apparatus employed for this purpose.

My invention comprises not only a new 20 method for operating kilns and drying lumber, but the construction of the kiln itself by which this method may be carried out.

The novel features of my invention which I believe to be new and upon which I desire 25 to secure a patent will be particularly defined in the claims terminating this specification.

The accompanying drawing shows a type 30 of construction for the apparatus which I now desire to use.

Figure 1 is a transverse sectional elevation of a kiln constructed in accordance with my invention.

Figure 2 is a horizontal or sectional plan 35 taken above the rail line of the kiln.

Figure 3 is a longitudinal sectional elevation taken approximately on the line 3—3 of Figure 1.

Figure 4 shows a typical section length- 40 wise of one of the air discharge flues.

The kiln proper, 1, may consist of any suitable type of construction which provides a kiln chamber of such size as will accommodate the loads placed upon the trucks and 45 at the same time leave suitable circulating spaces or flues about the load of lumber. The trucks upon which the lumber is placed for drying are loaded with the lumber piled on edge. The piling of the lumber upon the 50 trucks will be in accordance with previous practice, in which the successive layers of lumber are spaced apart by thin strips so as to make a vertical air circulating channel

between successive layers of the lumber. The trucks 2 may be of any construction 55 found suitable for such use.

The pile of lumber, as has been indicated in Figure 1, is of such size as compared with the cross sectional size of the kiln chamber, as to form therewith flues 10 located at each 60 side of the pile of lumber, and a flue 11 at the top of the lumber and another flue or space 12 beneath the lumber and above the floor of the kiln.

Between the rails of the kiln upon which 65 the trucks run, and below a flooring which as herein shown in below the level of the rails, is constructed a flue 14 into which air is withdrawn from the kiln chamber through a series of holes 16, which holes are made as 70 slots and which are smaller in cross sectional area near the end which is connected to the fan 3, shown in Figures 2 and 3. I have shown the fan which produces the circulation as being located at one end of the kiln 75 and beneath the trackway. This particular location is, however, not essential. The fan may be located at one side of the kiln or wherever it is found practical and convenient to locate it.

An air re-heating chamber 30 is provided 80 in which the air withdrawn from the kiln through the flue 14 is re-heated. It is then discharged from the fan through flues 15 located at each side of the kiln and provided 85 with discharge openings 4, shown in the form of slots extending crosswise of the flue. These slots are placed so as to run close up to the side of the kiln so that air discharged therefrom will be discharged directly into 90 the flue 10 formed at the sides of the pile of lumber.

To control the amount of air which is discharged from individual slots, deflecting 95 plates 40 are employed. These plates are of sheet metal and approximate to an L-shape. The lower or base section of the L is positioned inward from the upper wall of the flue and extending towards the direction from which the air comes. In other words 100 this base section of the deflector extends into the current of air. They will each act to catch a portion of the air and discharge it through the opening 4. If the air being discharged through one of these openings is 105 not sufficient it may be increased by bend-

ing the plate backward so as to throw the point of the lower arm or base of the deflector farther away from the roof of the flue. If, however, the amount of air discharged 5 through one of these openings is too much this can be reduced by bending upward the inner end of the deflector, as has been shown in connection with one of the deflectors in Figure 4.

10 The adjustability of the deflector plates makes it possible to control the rate of discharge from the flues throughout the length of the kiln thereby securing such a drying rate as conditions dictate. This rate of discharge 15 may be made even or variable at different points.

I prefer to provide the kilns also with air discharge openings 13 by which a small portion of the air may be discharged. The 20 amount of air discharged may be compensated for by taking in a like amount of air at the fan or at any other convenient point in the circulating system.

In carrying out the system for which 25 this kiln has been designed the air is drawn from the kiln through the flue 14. This flue is of such width and has its openings 16 so placed well under or inward from the side edges of the pile of lumber, that its 30 thrust action to pass air downward through the layers of lumber is upon that portion of the pile which forms a broad zone extending at each side of the center. Also the discharge of air from the flues 15 35 directly upward into the flues 10 between the lumber and the wall of the kiln, induces some of the air which has been flowing downward from the lumber near its outer side edges, to flow outwardly and 40 join the air discharged from the flues 15. This portion of the air does not go periodically back to the re-heater 30 but is circulated up through the flue 10 and thence is distributed through the channels of the 45 pile of lumber and is in part at least withdrawn during the next cycle of circulation to the re-heater. In consequence of this 50 action the amount of air circulating in the kiln is considerably in excess of the amount passed through the fan. While the fan handles the larger part of the air being circulated, part of it is circulated by the inducing action of the air discharged from flues 15 into the flues 10 in the kiln chamber. 55 This method of operation eliminates the necessity for using baffles beneath the side edges of the lumber pile and increases the 60 volume of the circulating air over the capacity of the fan or equivalent circulating means.

What I claim as my invention is:

1. The herein described method of drying lumber in a kiln which consists in placing the lumber in the kiln in piles having the lumber on edge and with layers spaced apart to provide vertical circulating channels therethrough, and with the top, sides and bottom faces of the pile spaced away from the corresponding walls of the kiln to provide circulation spaces between, withdrawing air from the kiln chamber beneath the piles, reheating the withdrawn air and discharging it upwardly into the kiln at the base of the flues between the lumber piles and the side walls. 70

2. The method of drying lumber in kilns which consists in placing the lumber within the kiln in piles having vertical circulating channels therein and of a size to leave air circulating passages entirely around the pile, causing a downward circulation through the pile by withdrawing air through openings located in the kiln floor well inward from the side margins of the pile, reheating the air so withdrawn and discharging it upward into the spaces between the side faces of the lumber pile and the kiln side walls, and thereby inducing part of the air flowing downwardly through the channels in the lumber pile near its side edges to flow laterally outward and join the upwardly discharged air. 80

3. The method of drying lumber in kilns which consists in placing the lumber within the kilns in piles having vertical circulating channels therein and of a size to leave air circulating passages entirely around, inducing a downward draft of air through a broad central band of the pile by withdrawing air through the floor under said band and through the side portions of the pile by discharge of heated air upward into the flues at the side of the pile. 90

4. A lumber drying kiln comprising a chamber having a trackway extending lengthwise thereof and adapted to receive lumber carrying trucks, an air-withdrawing flue located between the rails, an air discharging flue at each side of the track, said flues having openings close to the side walls of the kiln for discharging air upwardly, air reheating means and means for withdrawing air from the kiln through said central flue, passing it through the reheating means and discharging it upwards into the kiln from the side flues. 100

Signed at Seattle, King County, Washington, this 14th day of April, 1923.

MORITZ L. MUELLER.
